UNITED STATES PATENT OFFICE

136,821

DESIGN FOR AN INFANTS' TOILET SEAT

Martin Small, Chicago, Ill.

Application April 10, 1942, Serial No. 106,519

Term of patent 14 years

To all whom it may concern:

Be it known that I, Martin Small, a citizen of the United States of America, residing at Chicago, county of Cook, and State of Illinois, have invented a new, original, and ornamental Design for an Infant's Toilet Seat, of which the following is a specification, reference being had to the accompanying drawing, forming a part thereof, wherein:

Figure 1 is a perspective view of an infant's toilet seat, showing my new design.

Figure 2 is a top plan view showing the seat in folded position.

The essential features of my design reside in the configuration of the seat and arm portions of the article shown.

I claim:

The ornamental design for an infant's toilet seat, as shown and described.

MARTIN SMALL.
